DESIGN FOR A PUPILLARY MILLIMETER MEASURE

Michael B. Kendis, Kansas City, Mo.

Application May 26, 1947, Serial No. 139,287

Term of patent 7 years

(Cl. D52—1)

To all whom it may concern:

Be it known that I, Michael B. Kendis, a citizen of the United States, residing at Kansas City, in the county of Jackson and State of Missouri, have invented a new, original, and ornamental Design for a Pupillary Millimeter Measure, of which the following is a specification, reference being had to the accompanying drawing, forming a part thereof.

Fig. 1 is a top plan view of a pupillary millimeter measure, showing my new design.

Fig. 2 is a rear edge elevational view.

Fig. 3 is an end elevational view thereof, and Fig. 4 is an inverted plan view thereof.

I claim:

The ornamental design for a pupillary millimeter measure, as shown.

MICHAEL B. KENDIS.
